UNITED STATES PATENT OFFICE

FREDERICK H. PERRY, DECEASED, LATE OF BEVERLY, MASSACHUSETTS, BY EDNA A. PERRY, EXECUTRIX, OF BEVERLY, MASSACHUSETTS, ASSIGNOR TO UNITED SHOE MACHINERY CORPORATION, OF PATERSON, NEW JERSEY, A CORPORATION OF NEW JERSEY

COATING APPARATUS

Original application filed April 20, 1922, Serial No. 555,774. Divided and this application filed January 25, 1928. Serial No. 249,477.

This invention relates to apparatus for coating objects, it being particularly adapted for applying an adhesive to such work-portions as blanks which are to be assembled to form composite insoles, as by the machine disclosed in application Serial No. 555,774, filed April 20, 1922, by Edna A. Perry, executrix under the will of Frederick H. Perry, deceased, and of which the present case is a division. On May 1, 1928, the parent application became United States Patent No. 1,667,948.

Under certain conditions, as in the association of coating apparatus with such a machine as that referred to above, there are created problems as to compactness and convenience of arrangement, the supply of considerable quantities of the adhesive without waste, and the maintenance of this adhesive in proper condition for application, which it is the object of this invention to solve. Such object is attained by associating with an adhesive-applying mechanism, holding means or tables for the work-portions, which may be insole-blanks, two of these tables being shown, though there may be utility in the employment of but one. A table at one side of the applying mechanism may move toward and from said mechanism, which latter consists, as illustrated, of an applying roll and a pressure-roll, to deliver work-portions thereto. In the present embodiment of the invention, this movement is in two directions, as in a plane through the bite of the rolls and toward and from said plane. The latter movement facilitates the receipt of the work, as from a container, while the former effects its delivery for the coating operation. A work-holding table at the opposite side of the applying mechanism similarly moves toward and from it, advantageously receiving the coated work, and then, in its outward position, freeing said work from the applying mechanism for convenient transfer. The preferable manner of supplying adhesive is from a receptacle by a distributing device cooperating with the applying mechanism, as a head or nozzle extending along the applying roll. The supply is controllable, as by a valve movable in the head. To prevent flood-

ing and to minimize drip, there is provided means to render the adhesive-applying means effective in timed relation with the work-delivering means. This may be accomplished by connecting the valve which governs the adhesive-delivery and the work-delivering table to a common operating mechanism, which establishes the desired timing, as by allowing the adhesive to be supplied to the head only when the work is advancing toward the applying mechanism. An unobstructed flow of the adhesive is obtained by heating elements with which it contacts, for example at the receptacle, at the head, and along the intermediate pipes or connections. A desirable manner of applying heat to the adhesive-receptacle is by means of a surrounding water-tank. An adhesive-conduit leads from the receptacle to the applying means, and, since the receptacle is preferably removable for filling, there is a seal furnished between the conduit and receptacle, with means for applying pressure to the receptacle to render this seal effective. To retain the contents of the receptacle against discharge during such removal, a valve may be provided at the opening of the conduit, with a handle extending through the receptacle into proximity with its top and by which it may be conveniently closed and opened.

The accompanying drawings illustrate a particular embodiment of the invention,

Fig. 1 showing the improved coating apparatus in perspective, the figure being somewhat diagrammatic, with parts broken away;

Fig. 2 is a partial side elevation of the apparatus;

Fig. 3, a broken end elevation looking from the left in Fig. 2, with the receiving table removed;

Fig. 4, a transverse section on the line IV—IV of Fig. 2;

Fig. 5, a central vertical section through the adhesive-tank;

Fig. 6, a sectional view on the line VI—VI of Fig. 7, illustrating the valve for controlling the delivery of adhesive;

Fig. 7, a transverse section through said valve and the associated applying roll;

Fig. 8, a horizontal section through one side of the cement-tank; and

5 Fig. 9, a vertical section through one of the heating units associated with the cement-tank.

At 58 (see particularly Fig. 1) appears a 10 magazine or container adapted to contain a stack of insole or other blanks B (Fig. 2) to be operated upon, and from which they are delivered one by one under the control of separator devices 274 upon a feed or delivering table 616. This table is movable both 15 vertically and horizontally, and advances the blanks endwise into the grip of co-operating upper and lower rolls 618 and 620 of a coating mechanism, the lower roll 620 being adapted to apply cement or other adhesive to 20 the under face of each blank while the roll 618 puts pressure upon the work. The blanks are fed by the rolls 618 and 620 across 25 the top of a horizontally slidably receiving table 622, which advances them into position to be transferred for further operations upon them.

The table 616, which receives the composite blanks from the magazine 58, is shown as rectangular in form, and is supported and 30 adapted to slide horizontally upon rollers 624, which are arranged in pairs on the outer sides of two vertically disposed parallel side frames 626 projecting from a vertically slidable carriage 528. The pairs of rollers 624 35 are received in horizontal grooves 628 formed in the inner sides of two parallel flanges 629 depending from the opposite longitudinal edges of the table 616.

The carriage 528 is adapted to be raised to 40 elevate the feed-table 616 to a position immediately below the bottom of the stack in the magazine, so that, when the lowermost blank is released, it will not be permitted to fall through any substantial distance, but 45 will be received directly upon the feed-table, thus avoiding possible endwise displacement. To permit the carriage 528 to be raised and lowered, it is provided with two vertical ribs 630, which project at the outer 50 sides of the frame members 626, and each rib 630 is adapted to ride upon the peripheries of rollers 632, which are severally carried by upper and lower brackets 634 and 636, and are arranged to engage the opposite faces of 55 the ribs. The outer edge face of each rib 630 is guided by a pair of rollers 638, also carried by the brackets 634 and 636 (Fig. 3), both secured to a single support 640. The 60 weight of the carriage 528 and the various parts mounted thereon is counter-balanced by springs 642 secured at their lower ends to the carriage and at their upper ends to the bracket 634.

In order that the carriage 528 may be 65 reciprocated vertically to bring the feed-table

616 to the proper elevation to receive a blank from the magazine, and then to lower the table to the level of the top of the cement-roll 620, a rack-bar 646 is secured to the carriage, and is engaged by a segment 648 carried by a 70 rock-shaft 650 journaled in a bearing carried by the support 640. An arm 652 is fastened upon the rock-shaft 650 at the opposite end from the segment 648, and this arm is connected by means of a link 654 with one 75 end of a cam-lever 656 fulcrumed at 658. The cam-lever 656 carries a roll 660, which is received in a cam-groove 661 in the outer side of a cam-disk 662 fixed to a horizontal shaft 664 journaled in bearings on the frame 80 and continuously driven during the operation of the apparatus. The cam-disk 662 is rotated in correct time-relation with the associated movable elements, the groove engaged by the roll 660 being so designed as to cause 85 a single reciprocation of the carriage 528 for each operating cycle of the apparatus.

The feed-table 616 is so constructed that it does not extend beneath the extreme toe-end portion of the stack of blanks. Thus, when 90 a blank is received upon the table 616, its toe will project somewhat beyond the forward end of the table, as indicated at b in Fig. 2. After the table 616 has been lowered into the position in which it appears in Fig. 2, so that 95 the blank is supported at the proper level to be introduced between the rolls 618 and 620, said table is caused to slide horizontally upon the rollers 624 to present the toe-end of the 100 blank to the grip of said rolls.

The means for horizontally reciprocating the feed-table 616 comprises a segment 674, which engages a rack-bar 676 secured to the under side of the table. The lower portion of the segment 674 is pinned to a rock-shaft 678 journaled in the frame members 626. To actuate the rock-shaft 678, an arm 680, which is secured to the rock-shaft, is connected by means of a link 682 to one end of the upwardly extending arm of a bell-crank lever 684 fulcrumed at 686. The other arm of the bell-crank lever carries a cam-roll 688, which rides in a cam-groove 690 in the disk 662 at the opposite side from the groove 661 engaged by the roll 660. The cam-groove 690 is designed to reciprocate the feed-table 616 horizontally, once for each rotation of the disk 662. The link 682 is connected with the arm 680 by means of a pivot-stud which extends through a longitudinal slot 691 in the arm and is adjustably secured thereto. The slot 691 normally extends at such an angle with respect to the pivotal connection between the opposite end of the link 682 and the cam-lever 684 that, by shifting the position of the pivot-stud in the slot, the table may be adjusted toward and from the rolls 618 and 620, in accordance with the length of the sole-blanks being operated upon.

The vertical reciprocating movements of 130

the carriage 528 may be utilized to actuate the blank-separating devices through connections 693. When the separator devices act to release a blank from the bottom of the stack, the feed-table 616 occupies its uppermost position, removed from the rolls 618 and 620. After a blank has been deposited upon the table, this descends, and is advanced to present the projecting toe-portion to the grip of the rolls. These rolls are mounted to rotate in bearings supported by a pair of arms 704 and 706 rising vertically from the bracket 634, and are continuously actuated throughout the operation of the machine in directions to feed the blanks presented thereto from the table 616 between the rolls and upon the receiving table 622.

The lower or cement-applying roll 620 comprises a cylindrical shell, closed at its opposite ends and provided with a series of annular ribs 708 arranged parallel to each other and equally spaced apart across the external cylindrical surface of the roll. Intersecting the annular ribs 708 are a series of transverse ribs 710, which are equally spaced apart in parallel relation to each other. The ribs 708 and 710 provide a series of square, shallow pockets 712 adapted to contain cement which is to be applied to the blanks as they pass over the top of the roll. One end of the roll 620 is supported upon the inwardly projecting extremity of a short horizontal driving shaft 714 (Fig. 3), which is journaled in spaced-apart bearings 716 in the arm 704. To connect the roll 620 to rotate with the driving shaft 714, a collar 718 is pinned to the driving shaft and is provided with tongues 720 upon the inner end face of the collar at opposite sides of the shaft, these tongues being adapted to enter corresponding grooves formed in a hub 722 on the roll 620. At the opposite end, the roll 620 is journaled upon the inwardly projecting end of a horizontal stud 724, which is supported in the arm 706 and is axially aligned with the driving shaft 714. To permit removal of the roll 620 for cleaning or replacement, the stud 724 is mounted to slide on the arm 706, so that it may be withdrawn from the roll, and the supporting arm 706 is hinged upon a vertical pintle 726 (Fig. 2) carried by the bracket 634, to adapt it to be swung outwardly away from the arm 704. The stud 724 is provided with a nurled head, by means of which it may be moved in or out in its bearing on the arm 706. When the stud 724 has been withdrawn from the roll 620, and the arm 706 has been swung outwardly, the roll 620 may be readily removed from the driving shaft 714. A bayonet-joint connection 728 (Fig. 3) between the stud 724 and the arm 706 is provided for limiting the outward sliding movement of the stud in its bearing, and for permitting the stud to be locked in the inner or roll-supporting position.

The upper roll 618, which is shown as of the same diameter as the lower roll, also comprises a cylindrical shell closed at its opposite ends. The external cylindrical surface of the roll 618 is provided with a series of annular ribs 732 arranged in parallel relation to each other, and opposed to the corresponding annular ribs 708 of the lower roll. The roll 618 is supported at one extremity upon the inwardly projecting end of a short horizontal shaft 734, which is journaled in spaced-apart bearing-sleeves 736 normally resting upon the lower end walls of a pair of vertical slots 738 formed in the upper portions of the arms 704. The shaft 734 is driven from the shaft 714 through intermeshing spur-gears 740, one of which is secured to each of said shafts between the bearings thereof. The roll 618 is connected to turn with the shaft 734 by means of a collar 742 pinned to the shaft and provided with tongues 744, which project into corresponding grooves in a hub 746 on the roll. At the opposite end of the roll 618, a hub 748 is journaled upon the inwardly projecting end of a horizontal stud 750, adapted to slide longitudinally within a sleeve 752. The sleeve 752 is located within a vertical slot 754 at the upper extremity of the arm 706 and normally resting upon the lower end wall of said slot. Annular flanges 756, at the opposite ends of the sleeve 752, prevent its longitudinal displacement by engagement with adjacent faces of the arm 706. With this arrangement, the upper roll 618 is spaced from the lower roll 620 a distance somewhat less than the thickness of the blanks to be operated upon, while the slots 738 and 754 in the supporting arms 704 and 706 permit the roll 618 to yield upwardly as the blanks are introduced thereunder.

In order that the upper roll 618 may be yieldingly pressed against the sole-blank during the feeding of the latter across the cement-applying roll 620, the sleeves 736 and 752 are acted upon by springs 758 and 760, respectively. The spring 758 is seated within a recess 762 formed at the upper end of the arm 704, its lower end bearing against a transverse member 764, which connects the two sleeves 736 and partially encloses the upper gear 740. The upper end of the spring 760 is seated within a recess formed at the upper end of the arm 706, its lower end bearing against the sleeve 752. To adapt the stud 750 to be withdrawn from the roll 618, the stud is provided with a nurled head. A bayonet-joint connection 768 between the stud 750 and the sleeve 752 limits the outward sliding movement of the stud and permits the latter to be locked in its inner or roll-supporting position. To insure alinement of the shaft 734 and the stud 750, a vertical rod 770 rises from the transverse member 764 and extends through the coils of the

spring 758 and through an aperture at the extremity of the recess 762. A nut 772, threaded upon the upper end of the rod 770, bears against the top of the arm 704 and may be turned to vary the normal elevation of the bearing-sleeve 736, and consequently of the shaft 734. Secured to the outer end of the driving shaft 714 is a beveled pinion 774, which engages a beveled pinion 776 secured to the upper end of a shaft 778. This shaft 778 is so rotated from some source of power that the cement-rolls are driven continuously while the machine is in use.

Cement is supplied to the pockets 712 in the ribbed faces of the lower roll 620 through a distributing device supplied from a cement-reservoir 795. The distributing device is illustrated in Figs. 1, 6 and 7, and comprises an elongated head or nozzle 793, which is arranged at one side of the applying roll 620 and is rigidly secured at one end to a bracket 797 depending from the member 704. The head 796 is provided with a longitudinal bore 798 having a series of outlet-ports 799 terminating in a concave face 800 at one side of the head. The curvature of the face 800 corresponds to that of the roll 620. This face extends horizontally throughout the length of the roll 620, and is arranged closely adjacent the upper edge faces of the ribs thereon. The distributing head 796 is connected by means of a pipe or conduit 802 with the cement-reservoir 795. Two of these pipes are illustrated for connection to plural coating apparatus, but one of which appears herein.

To prevent waste of the cement, it is supplied to the roll 620 only during such time as a sole-blank is being fed thereto. To this end, the outlet-port 799 in the distributing head 796 is adapted to be opened and closed by means of a valve, which is operated in timed relation with the movements of the feed-table 616. The valve comprises a tube 803, which fits closely within the bore 798 in the head, and through which the cement is caused to flow. The valve-tube 803 is provided with a series of outlet-ports 804 adapted to register with the ports 799 in the head. The tube 803 may be oscillated to bring the ports 804 alternately into and out of registry with the ports 799, thereby causing an intermittent flow of cement from the head to the roll. The oscillatory movement of the valve-tube 803 is derived from the cam-disk 662, which actuates the feed-table 616. To this end, the valve-tube 803 is connected, in the following manner, with the cam-lever 684, actuated by the cam-disk. As shown in Fig. 1, an arm 805 is rigidly secured to one end of the valve-tube 803, and is connected by a link 806 with one end of an arm 807 which is, in turn, rigidly secured to the outer end of a rock-shaft 808. The rock-shaft 808 is journaled in a bearing 809 rigidly supported by

a portion of the frame, and carries at its inner end a depending arm 810. The lower extremity of the arm 810 is forked, as shown at 811, to straddle an extension of the pin which pivotally connects the cam-lever 684 with the link 806. With this construction, as the cam-lever 684 is swung toward the right, viewing Fig. 1, to slide the feed-table 616 toward the cement-applying rolls for the purpose of introducing a sole-blank therebetween, the valve 803 will be opened to permit a flow of cement to the lower roll 620. When the cam-lever 684 is moved in the opposite direction to carry the feed-table away from the rolls, the valve 803 is closed to shut off the supply of cement.

To permit adjustment of the amount of cement supplied to the roll 620 when the valve 803 is opened, the arm 805 is provided at its outer end with a longitudinal slot 812 adapted to receive one end of a stud 813, upon the opposite end of which the link 806 is pivoted. Adjusting means, such as a screw 814, may be employed for shifting the position of the stud 813 in the slot. With this construction, relative angular positions of the link 806 and the arm 805 may be so adjusted that the ports 799 and 804 will not be brought completely into registry with each other when the valve 803 is opened. In this way, the amount of cement supplied to the roll 620 as each blank is fed across it may be varied at will. The outer end of the valve-tube 803 is extended beyond the arm 805 to enter a notch in an arm 815, which is pivotally mounted upon the frame-arm 706. The notch in the arm 815 provides a bearing for the valve 803, so that the distributing head 796 is more firmly held against movement. The arm 815 may be swung upwardly to disengage the notch therein from the extremity of the valve-tube 803 to permit the removal of the rolls 618 and 620 or of the valve 803.

As best shown in Fig. 5, the cement-reservoir 795 comprises a cylindrical receptacle 817 for cement. To maintain the cement in the receptacle 817 at the requisite temperature to insure its free flow, the receptacle is enclosed within a hot-water tank 818 supported by brackets secured to the frame. The tank comprises a cylindrical casing of a greater diameter than the cement-receptacle. The receptacle is supported by a pair of bosses 819 projecting from it and being seated within sockets formed in a pair of bosses 820 rising from the bottom of the tank. The space between the bottom walls and the cylindrical side walls of the receptacle and tank is filled with water, and a gage 821 may be provided at the side of the tank to indicate the water level. The tank, which may be conveniently filled through a cup 822, has at its upper end a circular opening of a diameter sufficiently large to permit the removal of the cement-receptacle. This

opening is normally closed by a cover 823, which slightly overlaps an annular rim furnished by a flange 824 projecting inwardly from the upper end of the cylindrical side wall of the tank. Depending from the marginal portion of the cover 823 is a pair of lugs 825, which are adapted to enter a pair of notches 826 in the flange 824 when the cover is being placed upon the tank. To permit the cover to be locked in position, the outer edges of the lugs 825 are provided with grooves 827 adapted to receive the flange 824. After the cover 823 has been placed upon the tank, with the lugs 825 projecting through the notches 826, the cover is turned, thus moving the lugs 825 out of registry with the notches and bringing the grooves 827 into engagement with the flange 824. The cement-receptacle 817 is filled through a circular opening in its top, which is normally closed by a removable cover 828. The cover 828 is kept closed, and the receptacle 817 is prevented from rising, under the influence of its buoyancy in the water-tank 818, by means of a screw 830, which is threaded vertically through the central portion of the cover 823, the lower end of this screw being seated in a central recess in the cover 828. The screw 830 is provided with a hand-wheel 831, by means of which it may be readily turned to securely hold the cement-receptacle against the bottom of the tank, and the cover 828 against the top of the receptacle. The screw 830 serves also to lock the flanges 825 against the under side of the flange 824, thus securely holding the cover 823 in closed position.

To facilitate the free flow of the cement through the conduits 802, means is provided for applying pressure to the cement within the receptacle by an air-pump 832 mounted upon the hand-wheel 831 in axial alignment with the screw 830. The interior of the pump 832 is connected with the interior of the cement-receptacle by means of an air-passage 833 extending axially through the screw. At the lower end of the screw, the air-passage communicates with a central opening 834 in the cover 828. To prevent leakage of air when the pump 832 is being operated, a gasket 835 is interposed between the lower end of the screw 830 and the base of the recess in the cover 828 which is entered by said screw. A valve 836 prevents outward leakage of air from the cement-receptacle.

Cement flows from the receptacle 817 into a central opening 838 in the base of the reservoir, the flow being controlled by a normally open valve 839. Leading from the opening 838 are two radiating passages 840, which are inclined slightly downward. These passages 840 terminate severally at the lower faces of the bosses 819 on the bottom of the receptacle, and communicate with vertical

passages 841 in a pair of valve-casings 842 depending from the base of the water-tank 818, each vertical passage 841 terminating at its upper end in the base of the recess in the respective boss 820. To prevent leakage of cement at the junctions of the passages 840 and the passages 841, a gasket 843 is interposed between the base of the recess in each boss 820 and the end face of the corresponding boss 819. The passages 841 are severally connected at their lower ends by means of a coupling device 844 with the upper ends of conduits 802. In the present instance, but one of these conduits is in use, this leading to the cement-supply valve 803. The valve-casings 842 are provided with manually operable valves 845 for shutting off the flow of cement from the reservoir 795.

The water in the tank 818 may be maintained at a relatively high temperature by means of a series of electric heating units 846, which are secured at their lower ends to the bottom of the water-tank and project into the space between the cylindrical walls of the cement-receptacle and the tank. To insure that the cement will be maintained at the required consistency when applied to the rolls, each cement-conduit 802 is arranged between two similar conduits 848 (Figs. 1 and 5), through which a circulation of hot water is maintained. The ends of the conduits 848 remote from the water-tank are severally connected to the opposite ends of a passage 849 (Fig. 7) in the distributing-head 796, this passage extending horizontally back and forth through the head at one side of the valve or tube 803.

The upper end of one of the hot-water conduits 848 of each pair is connected through its coupling device 844 with the lower extremity of a passage 850, which extends upwardly through the corresponding valve-casing 842 and communicates with the bottom of the tank 818. The upper extremity of the other conduit 848 of each pair is connected, by means of the coupling device just referred to, with a second passage 851 in the valve-casing, and communicates at its upper extremity with the lower end of a standpipe 852. The standpipe 852 rises within the space between the receptacle and the tank to a point somewhat below the normal water-level and is open at its upper end. Manually operable valves 853 are provided in the passages 850 and 851, in each of the valve-casings 842, by means of which the circulation of the heating water may be shut off.

The distributing head 796 is adapted to be heated by means of an electrical heating unit, which may be inserted in a longitudinal recess 854 (Figs. 6 and 7), which extends throughout the length of the head immediately below the valve-tube 803. The conduits 848 will be filled with hot water from the tank 818. When reaching the passages 849 in

the distributing head, the temperature of the water will be raised by the heat derived from the heating unit in the recess 854, in addition to that from the units 846, thus increasing the circulation through the conduits 848, this circulation being in the direction indicated by the arrows in Fig. 5. It will be seen that the temperature of the cement, as it is applied by the distributing head to the roll 620, will be maintained by means of the heat derived directly from the heating unit within the recess 854, as well as from the hot water circulating through the passages 849. The source of heat at 854 may be utilized at such times as when first starting the machine in operation. Its continued use might have a too great drying effect upon the cement and clog the delivery device.

It is desirable that means be provided whereby, when the cement-receptacle 817 is being inserted within the tank 818, said receptacle may be readily positioned, so that the bosses 819 carried thereby will enter the recesses in the bosses 820 at the bottom of the tank. Accordingly, positioning devices are provided, comprising a plurality of vertical guide-rods 856, which are secured to the inner face of the side wall of the tank, as shown in Figs. 5 and 8, and a plurality of co-operating guide-blocks 857, which project outwardly from the side walls of the receptacle adjacent its upper and lower ends. The guide-rods 856 are adapted to be engaged by V-shaped positioning notches 858 formed in the outer faces of the guide-blocks 857. By turning the receptacle until the notches are in engagement with the rods, the bosses 819 will be brought into alignment with the recesses in the bosses 820. The rods both act as guides and provide lateral support for the receptacle.

When removing the cement-receptacle from the water-tank for the purpose of refilling the former, it is desirable to shut off communication between the interior of the receptacle and the central passage 838 in the bottom thereof by closing the valve 839, thus preventing the water within the tank 818 from rising into the interior of the receptacle. As shown, the valve 839 comprises a sleeve 859, which is screw-threaded into a boss 860 rising centrally from the bottom of the receptacle. The lower end of the sleeve communicates with the opening 838. A short distance above the lower end of the sleeve, four radial passages 861 connect its interior with the interior of the receptacle. The screw-threaded portion of the sleeve extends just above the radiating passages 861, and has an annular flange 862 formed above said threaded portion. By turning the sleeve by means of a handle at its upper extremity, the passages 861 may be brought below the upper end of the boss 860, and the shoulder formed by the lower side of the flange 862 tightly pressed against the upper end of said boss. In this

way, communication between the interior of the cement-receptacle and the central passage 838 is completely shut off.

It is also desirable to provide means for preventing the cement-receptacle 817 from being lifted by the buoyancy of the water in the tank 818 when the cover 823 is removed from said tank. To effect this, a screw 863 extends upwardly through the bottom of the tank, and is threaded into a boss 864 depending from the bottom of the receptacle. Loosening the screw permits the removal of the receptacle. Washers may be provided for preventing leakage of the water around the screw.

The receiving table 622 (Figs. 1 and 2), to which the coated blanks are delivered by the rolls 618 and 620, comprises a horizontal rectangular plate mounted to slide longitudinally upon a pair of parallel guide-ribs 865 rising from a bracket 866 carried by the frame. The table 622 is provided with flanges 867 depending from its lateral edge-portions, which engage the outer edges of the guide-ribs 865, and the flanges 867 have inwardly turned ribs 868, which project beneath the guide-ribs 865 to prevent upward displacement of the table. The table 622 is normally located with its rear extremity close to the rolls, and is moved away from them to withdraw the heel-ends of the sole-blanks sufficiently from the positions in which they are delivered to permit said blanks to be freely lifted vertically, without being bent downward at the heel-ends. To accomplish this, the receiving table is connected by means of a link 869 with any transferring or other mechanism with the movements of which it is desired to synchronize those of the table.

To insure that the blanks delivered by the cementing rolls 618 and 620 stop upon the table 622 in the correct position for transfer therefrom, there is associated with the table a locating arm or stop-abutment 1001 (Fig. 1). This abutment is pivoted at 1002 at the outer side of its table, and is normally held out of the path of the transferring mechanism by a spring 1004 connecting the outer extremity of the arm beyond the pivotal point with a pin 1006 projecting from the side of the table. Mounted upon a bracket 1008 rising from a portion of the frame is a horizontal rod 1010 situated in alignment with the portion of the arm 1001 to which the spring is attached. When the table is in its inner or receiving position, adjacent the rolls 618 and 620, the end of the rod 1010 contacts with the arm, swinging it about its pivot against the tension of the spring to hold it in its active position across the table. At this time, a curved portion 1012 of the arm lies in the path of the sole-blank as it is advanced by the rolls across the table, this portion 1012 being formed to engage the toe of such blank. The rod 1010 is preferably arranged to move

longitudinally through the opening in the bracket 1008, being held in place therein by a set-screw 1014. Upon loosening this set-screw, the rod may be adjusted and again 5 fixed in position by the screw to vary the angle which the arm makes with the line of advance of the sole, and therefore the distance of the curved stop-surface from the bite of the rolls 618 and 620. This distance is so 10 adjusted that it is equal to the length of the piece delivered by the rolls. That is, just as the heel-end of the piece has passed the bite of the rolls, the toe-end will contact with the stop-portion 1012, preventing the piece from 15 being fed past the chosen position. Then, as the table moves over the rolls in preparation for the engagement of the blank by the transferring mechanism, the extremity of the arm 1001 leaves the end of the rod 1010, permitting 20 the former to be drawn to one side by its spring 1004 out of the path of such mechanism, this being as is illustrated in Fig. 1.

To outline the operation of the apparatus, the table 616 is in its elevated relation, just 25 below the magazine 58. At the same time, the table 622 has its inner end close to and substantially in the same horizontal plane as the bite of the rolls 618 and 620. In these positions, the tables are temporarily 30 held, awaiting the beginning of an operating cycle. The separator devices 274 being operated, a single insole-blank is released from the magazine, falling on the table 616 with its toe-end projecting from the extremity of 35 the table toward the rolls. Now the table descends until the blank is on the level of the bite of the rolls, and then is advanced horizontally to present the overhanging end of the blank to the rolls. These, in their rotation, draw it between them, the upper or pressure-roll 618 forcing the piece down upon the lower or cement-applying roll 620. Cement from the receptacle 817, heated by the water within the tank 818 and by that in the 40 pipes 848 on each side of one of the cement-delivery pipe 802, flows to the distributing head 796. As the table 616 starts forward with the blank, the valve 803, in which the pipe 802 terminates, is opened by its connection to the table-actuating mechanism, and permits the cement to flow through the passages 799 to the surface of the roll 620, said valve being again closed upon the opposite or outward movement of the table. In this 45 way, by regulating the extent to which the valve opens by adjustment of the screw 814, the supply of cement may be made sufficient without danger of flooding. From the rolls, the coated blank passes upon the receiving 50 table 622 against the locating portion 1012 of the lever 1001, being thus positioned upon the table in the proper relation for engagement by transferring means. The blank having been delivered and located in this way, the table 622 travels away from the rolls to 55 its outer position, where the heel-end of the blank is completely free from the rolls, so that its vertical movement will not be interfered with. At the same time, the lever 1001, released from its contact with the rod 1010, 70 is restored by its spring to its normal position clear of the blank. This, with the return of the delivering table 616 to its initial location beneath the magazine, completes the cycle of the apparatus. 75

Having described the invention, what is claimed as new and is desired to be secured by Letters Patent of the United States is:

1. In a coating apparatus, adhesive-applying means, variable means for feeding adhesive to the applying means, means for advancing a work-portion to the applying means, and means for varying the feeding means to start the feed of adhesive during the advance of the work-portion. 80
2. In a coating apparatus, adhesive-applying means, means traveling toward and from the applying means for delivering a work-portion thereto, and means for starting and stopping the feed of adhesive in connection with every movement of the delivering means. 90
3. In a coating apparatus, adhesive-applying means, means for feeding adhesive to the applying means, reciprocatory means for advancing a work-portion to the applying means, and means for starting the feed of adhesive during the advance of the delivering means and for stopping such feed during the retreat thereof. 95
4. In a coating apparatus, applying mechanism, an adhesive-receptacle, connections between the receptacle and applying mechanism including a controlling device, intermittently movable means for advancing work to the applying mechanism, and means for operating the controlling device and advancing means in timed relation. 105
5. In a coating apparatus, applying mechanism, an adhesive-receptacle, connections between the receptacle and applying mechanism, a valve included in the connections, a table movable to advance work to the applying mechanism, and mechanism common to and arranged to operate the table and valve. 110
6. In a coating apparatus, applying mechanism, an adhesive-receptacle, connections between the receptacle and applying mechanism including a controlling device, intermittently movable means for advancing work to the applying mechanism, means for operating the controlling device and advancing means in timed relation, and means arranged to vary the movement of the controlling device. 120
7. In a coating apparatus, applying mechanism, an adhesive-receptacle, connections between the receptacle and applying mechanism, a valve included in the connec- 125

- tions, a table movable to advance work to the applying mechanism, operating mechanism common to the table and valve, and adjusting means included between the operating mechanism and valve.
5. 8. In a coating apparatus, a rotatable applying roll, a distributing head extending along and conforming to the curvature of the roll, an adhesive-receptacle, adhesive-supplying connections between the receptacle and head, and a valve associated with the head and controlling the flow of adhesive through the supplying connections.
9. In a coating apparatus, a rotatable applying roll, a distributing head extending along the roll, an adhesive-receptacle, adhesive-supplying connections between the receptacle and head, a valve associated with the head and controlling the flow of adhesive through the supplying connections, and operating connections for the valve including and adjustable element arranged to variably control the movement of said valve.
10. A coating apparatus having, in combination, a cement-applying roll, means co-operating therewith to advance work across the roll, a distributing head for supplying cement to the roll, means for supplying cement to the head, a valve for controlling the delivery of cement from the head, and means for opening and closing the valve intermittently.
11. A coating apparatus having, in combination, feed mechanism for periodically advancing work-portions, a cement-applying roll, a co-operating feed-roll between which said work-portions are successively introduced by said feed mechanism, an elongated cement-distributing head extending throughout the length of the cement-roll in close proximity thereto and having a plurality of outlet-ports therein, means for supplying cement to said head, and means for adjusting the size of the outlet-ports to vary the flow of cement.
45. 12. In a coating apparatus, means for applying an adhesive to the work, and adhesive-receptacle, and a distributing head connected to the receptacle having openings the delivery through which is controlled by the co-operation with the applying means below its upper portion, and means associated with said upper portion of the applying means for pressing work against it.
55. 13. In a coating apparatus, an upper pressure-roll, a lower applying roll, and adhesive-distributing head extending along the side of the applying roll, and adhesive-receptacle, and an adhesive-supplying pipe connecting the receptacle and head.
65. 14. In a coating apparatus, an upper pressure-roll, a lower applying roll, an adhesive-distributing head extending along the side of the applying roll, an adhesive-receptacle, and an adhesive-supplying pipe connecting the
- receptacle and head, and a valve movable in the head and through which the pipe delivers.
15. In a coating apparatus, a rotatable roll for applying an adhesive to the work, an adhesive-receptacle, a distributing head connected to the receptacle and delivering to the applying roll by direct co-operation therewith and means for heating the receptacle and head, said means surrounding the receptacle and extending through the head along the applying roll.
16. In a coating apparatus, means for applying an adhesive to the work, an adhesive-receptacle delivering to the applying means, a tank for a heating liquid surrounding the receptacle, and means situated within the tank for creating a circulation therein.
17. In a coating apparatus, a rotatable applying roll, a distributing head extending along the roll, an adhesive-receptacle, adhesive-supplying connections between the receptacle and head, and means for heating the connections.
18. In a coating apparatus, a rotatable applying roll, a distributing head extending along the roll, an adhesive-receptacle, adhesive-supplying connections between the receptacle and head, means for heating the receptacle, and means extending from said receptacle-heating means for heating the connections.
19. In a coating apparatus, an applying roll, an adhesive-distributing head extending along the side of the applying roll, an adhesive-receptacle, an adhesive-supplying pipe connecting the receptacle and head, and heating means associated with the adhesive-supplying pipe.
20. In a coating apparatus, an applying roll, an adhesive-distributing head extending along the side of the applying roll, an adhesive-receptacle, an adhesive-supplying pipe connecting the receptacle and head, a heating tank associated with the receptacle, and a pipe extending from the tank in proximity to the adhesive-supplying pipe.
21. In a coating apparatus, an applying roll, an adhesive-distributing head extending along the side of the applying roll, an adhesive-receptacle, an adhesive-supplying pipe connecting the receptacle and head, a heating tank associated with the receptacle, a pipe extending from the tank in proximity to the adhesive-supplying pipe, an electrical heating unit acting upon the tank, and an electrical heating unit associated with the head.
22. In a coating apparatus, an applying roll, an adhesive-distributing head extending along the side of the applying roll, an adhesive-receptacle, an adhesive-supplying pipe connecting the receptacle and head, a heating tank associated with the receptacle, a pipe extending from the tank in proximity to the adhesive-supplying pipe, an electrical heat-

- ing unit situated in the tank, and an electrical heating unit carried within the head.
23. In a coating apparatus, means for applying an adhesive to the work, a tank, an adhesive-receptacle situated within the tank and being removable therefrom, a conduit connecting the receptacle and applying means, means for sealing the connection between the receptacle and conduit, and means arranged to exert pressure upon the receptacle to render the seal effective.
24. In a coating apparatus, means for applying an adhesive to the work, a tank, an adhesive-receptacle provided with a cover, said receptacle being situated within the tank and being removable therefrom, a conduit connecting the receptacle and applying means, means for sealing the connection between the receptacle and conduit, and means carried by the tank for exerting pressure upon the cover, such pressure rendering the sealing means effective.
25. In a coating apparatus, adhesive-applying mechanism, a tank, an adhesive-receptacle situated within the tank and being removable therefrom, a conduit connecting the receptacle and applying mechanism, a gasket interposed between the tank and receptacle about the conduit, and means for forcing the receptacle against the gasket.
26. In a coating apparatus, adhesive-applying mechanism, a tank, an adhesive-receptacle situated within the tank and being removable therefrom, a conduit connecting the receptacle and applying mechanism, a cover for the receptacle, and a pressure member movable upon the tank and bearing against the cover.
27. In a coating apparatus, adhesive-applying means, an adhesive-receptacle delivering to the applying means, means at the bottom of the receptacle for controlling the flow of adhesive therefrom, and means extending through the contents of the receptacle and terminating therein to operate the controlling means.
28. In a coating apparatus, adhesive-applying mechanism, an adhesive-receptacle, a conduit opening through the bottom of the receptacle and connected to the applying mechanism, a valve at the opening of the conduit from the receptacle, and a valve-handle extending through the receptacle into proximity with its top.
29. In a coating apparatus, means for containing work-portions, means for applying an adhesive to said portions, an interposed table, means for removing a work-portion from the containing means and delivering it to the table and means for moving the table away from the applying means and into proximity with the containing means to receive a work-portion therefrom and for moving said table away from the containing means and into proximity with the applying means to deliver a work-portion thereto.
30. In a coating apparatus, means for applying an adhesive to the work, means for holding work-portions at opposite sides of the applying means, and means for moving both holding means toward and from the applying means and stopping their movements in predetermined positions.
31. In a coating apparatus, means for applying an adhesive to the work, means for holding work-portions at opposite sides of the applying means, means for moving both holding means toward and from the applying means and stopping their movements in predetermined positions, and means for moving one of the holding means in another direction.
32. In a coating apparatus, means for applying an adhesive to the work, means for holding work-portions at opposite sides of the applying means, means for moving both holding means toward and from the applying means and stopping their movements in predetermined positions, means for moving one of the holding means in another direction, and means for delivering the work-portions one by one to the last-mentioned holding means.
33. In a coating apparatus, means for applying an adhesive to the work, means for holding work-portions at opposite sides of the applying means, said applying means receiving the work-portions from one holding means and delivering them to the other holding means, and means for moving bodily both holding means toward and from the applying means.
34. In a coating apparatus, a container for work-portions, a holder occupying a position at the container to receive a work-portion with one extremity projecting beyond the holder, means for applying an adhesive to the work-portion, and means for moving the holder and arranged to deliver the projecting end of the work-portion to the applying means.
35. In a coating apparatus, a container for work-portions, means for applying an adhesive to the work-portions, a table between the container and applying means, and means for moving the table vertically toward and from the container and horizontally toward and from the applying means.
36. In a coating apparatus, coating mechanism including a coating-applying roll, and a table receiving work from the coating mechanism and movable toward and from said coating mechanism to deliver to the applying roll.
37. In a coating apparatus, coating mechanism including co-operating rolls, and a work-supporting table movable toward and from the bite of the rolls at the delivery side.
38. In a coating apparatus, coating mech-

anism including co-operating rolls, and a work-supporting table movable toward and from a plane through the bite of the rolls and into and out of said plane.

5 39. In a coating apparatus, a work-container, coating mechanism, and a work-supporting table movable in one direction toward and from the container and in another direction toward and from the coating mechanism.

10 40. In a coating apparatus, coating mechanism, and a plurality of work-supporting tables movable toward and from the coating mechanism.

15 41. In a coating apparatus, coating mechanism, a work-supporting table movable toward and from the coating mechanism at each side thereof, and actuating mechanism arranged to move the table at the receiving side

20 of the coating mechanism toward and from said coating mechanism and at the same time to hold the opposite table stationary and thereafter to move such opposite table away from the coating mechanism.

25 42. In a coating apparatus, coating mechanism, a work-supporting table movable toward and from the coating mechanism at each side thereof, and actuating mechanism arranged to move the table at the receiving

30 side of the coating mechanism toward and from said coating mechanism and at the same time to hold the opposite table stationary and thereafter to move both tables away from the coating mechanism.

35 In testimony whereof I have signed my name to this specification.

EDNA A. PERRY,
*Executrix of the Will of Frederick H. Perry,
Deceased.*
